(54) **COTTON, MANUFACTURE**

(76) Inventor: **Elisha Congdon**

Wisha Congdon.
Letters Patent.

The schedule referred to in these Letters Patent and making part of the same containing a description in the words of the said Wisha Congdon himself of his improvement in the process of manufacturing cotton.

In the process of manufacturing cotton, after the cotton has ^{been} passed through the picker. It is then weighed into parcels of such weight as is necessary to form a ball of proper thickness to make the roping of such size as may be wanted; each one of these parcels is of the proper size to make what is called a batt; in which process the cotton so weighed is fed on to an apron on the back side of the breaker, and from thence passed through the breaker, and completed on what is called the batt cylinder on the other side.

It is of the utmost consequence that these batts should be uniform and equal, each one of the same length and weight. When the cotton for a batt has been wound on the batt cylinder by the operation of the breaker card, the batt is taken from the cylinder by a child employed for that purpose, by taking it on the sides, with each hand and tearing it apart; which operation makes the ends of the batts uneven, unequal, and also stretches the batts more or less in length; the consequences of which are, unequal yarn is produced from batts to be taken off. To obviate such difficulties, and also to save a very considerable portion of the labour usually bestowed, is the object and purpose of Congdon's Batt Breaker; by the construction of which, when ever the cotton which has been weighed and placed in the apron & from thence has been run into the breaker, and discharged itself, on the batt cylinder, the batt is then broken by the bursting of the door, on the cylinder, constructed for that purpose,

The process of breaking the batt by Congdon's Batt Breaker. The cotton being spread on a cloth attached to a wooden roller about 2 $\frac{1}{2}$ inches in diameter, lettered L, the cloth being sufficiently long to receive the cotton (16 $\frac{1}{2}$ in. may be varied according to the weight of the batt wanted,) it is then

wound upon the roller, and placed on two stands, A, fastened to the end of the feeding frame, which stands ... hang upon a pivot A, and the end of the cloth or apron is then passed between two wooden roller placed directly back of the iron fluted rollers, which are also attached to the feeding frame; when rollers revolve fast enough to surround the lap cloth, and pass the cotton into the card, when this cloth is un wound it moves those stands A that the batt roller is placed on, forward, and raises the lever B, which is also connected to the feeding frame, which by the aid of this lap cloth it draws through those wooden rollers that are placed back of the iron fluted rollers out of gear; and these rollers being attached to one end of the rod C, passing along the side of the card to the batt cylinder or front of the machine. On the other end of this rod is attached a knee D, which knee is fastened to the collander roller stand, which by those two wooden roller, coming out of gear bring the knee D, in contact with a spring catch E, which is placed on the knee of the batt cylinder, and holds the lid F, down that breaks the batt. When this knee comes in contact with a pin G placed in the spring catch, this spring being crowded off, allows the spring H, placed on the end of the cylinder to open the lid F and break the batt.

It is that by passing an inclined plane placed on the front of the card. - K is a spring that throws the wooden rollers out of gear when over the cotton is expanded which has been placed on the apron (and is also attached to the feeding frame;) L is an instrument by which the rollers are thrown into gear, when a new apron with cotton is put into the stand A, which instrument L is also attached to the feeding frame M, is a spring which operates on the lever B, and forces it up while the cotton is running into the card, and is also attached to the feeding frame. (This machine not only breaks the batts more correctly than they can be broken by hand, but has other advantages in breaking the batts by water. In breaking by hand it is attended with several difficulties the most important ones are; when a child has spread the batts in the usual way on the back side of the machine, it will neglect to give notice that the batt is out; and in consequence of this neglect the whole or part of two batts, will run through the machine and consequently every the number

of the yarn considerably. When the batts in this machine are run through, the machine cuts and breaks of itself, and it is impossible to make with it what is termed double batty; this is attended with great and serious injury in manufacturing, and it is wholly impossible to make a child do this kind of work, without its making double batty more or less every day.

In consequence of its breaking by machinery, it does away all small help, and obviates this difficulty. The same work done by seven or eight children is now done by this machine, and one small boy is capable of tending ten breakers, and may be safely calculated to save one half the labour in preparing it to pass into the finisher. This machine is easy in its movements, simple in its construction, and correct in its operation.

City of Norwich, March 1st 1824.
